UNITED STATES PATENT OFFICE.

GUIDO BONDI, OF DAYTON, KENTUCKY.

MOLD FOR MAKING MUSICAL INSTRUMENTS.

1,369,381.

Specification of Letters Patent. Patented Feb. 22, 1921.

Application filed September 29, 1919. Serial No. 327,098.

To all whom it may concern:

Be it known that I, GUIDO BONDI, a citizen of the United States, residing at Dayton, in the county of Campbell and State of Kentucky, have invented new and useful Improvements in Molds for Making Musical Instruments, of which the following is a specification.

This invention relates to musical instruments, particularly to those of the wind actuated type, and has for its object the provision of a novel form of musical instrument and peculiarly constructed mold members for forming the same from plastic material.

With the above and other objects and advantages in view, the invention consists in the details of construction to be hereinafter more fully described and claimed, and illustrated in the accompanying drawings in which—

Figure 1 is a plan view of the mold members disconnected,

Fig. 2 is a perspective view of one of the inner mold members,

Fig. 3 is a perspective view of the other inner mold member,

Fig. 4 is a cross sectional view through the outer mold members with the plastic material therein and the inner mold members in position,

Fig. 5 is a similar view with the inner mold members removed and the outer mold members assembled,

Fig. 6 is a longitudinal sectional view therethrough,

Fig. 7 is an elevation of one side of the completed instrument, and

Fig. 8 is an elevation of the opposite side.

Referring more particularly to the drawings, the numerals 10 and 11 designate the outer mold members which may be formed of any suitable material such as plaster of Paris and which are so formed as to mate, one member carrying projections 12 and the other having recesses 13 conformingly receiving the projections. These mold members 10 and 11 are hollowed out or recessed, as shown at 14 and 15, respectively, to give the proper shape to the instrument to be molded and these recesses 14 and 15 have communicating therewith smaller laterally extending recesses 16 and 17, respectively.

The numeral 18 designates one inner mold member which is formed of suitable material such as metal and which is adapted

for disposition within the mold member 10. This member 18 is formed as an elongated body having substantially the same contour as the hollow 14 in the mold 10 and has formed thereon a plurality of projections 19, for a purpose to be described. This member 18 is also provided with ring 20 serving as a handle. The numeral 21 designates the other inner mold member of substantially the same contour as the hollow 15 in the mold member 11 and is provided with a plurality of projections 22 and also with a handle 23.

In the use of the device, plastic material, such as clay or the like is placed within the hollow 14 in the mold 10 and the member 18 is then placed within the mold and pressed firmly downwardly until the projections 19 thereon pass entirely through the plastic material A and engage against the inner wall of the mold. The surplus material which squeezes up beyond the top of the mold member is then scraped off to be flush. Plastic material B is then placed in the mold member 11 and the inner mold member 21 is pressed thereinto in the same manner until the projections 22 pass through the material and engage the inner wall of the mold. The inner mold members 18 and 21 are then removed and the mold members 10 and 11 are then superposed and pressed firmly together to unite the edges of the plastic material. After the device has stood a sufficient length of time for the plastic material to become set, the mold members 10 and 11 are separated and the instrument C removed.

The instrument C will then be found to consist of a hollow body 24 of substantially torpedo shape and having a laterally extending mouth piece 25. The body will have extending through one side thereof a plurality of holes 26 of different sizes formed by the projections 19 on the inner mold member 18 and upon its other side the body will have a plurality of holes 27 formed by the projections 22 on the mold member 21. The holes 26 are adapted to be covered by the fingers of the operator and the holes 27 are adapted to be covered by the thumbs. It is preferable that the entire instrument be painted and it may also be advisable to have numerals and note indicia inscribed upon its surface adjacent the holes 26 and 27. The mouth piece 25 has formed therein a passage 28 which is very small and

which extends into the interior of the body 24 and this passage is formed preferably by inserting a suitable shaped strip of material in the lateral recesses 16 and 17 in the mold members 10 and 11 after the plastic material is disposed therein.

The instrument is played by blowing through the mouth piece 25 and manipulating the fingers and thumbs to uncover the 10 desired ones of the holes 26 and 27.

From the foregoing description and a study of the drawings it will be apparent that I have thus provided a very simple mold device for forming a musical instrument 15 in a very simple and efficient manner so that the cost of production of the instrument will be slight.

While I have shown and described the preferred embodiment of my invention it is 20 of course to be understood that I reserve the right to make such changes in the form, construction, and arrangement of parts as will not depart from the spirit of the invention or the scope of the subjoined claim.

Having thus described my invention, I 25 claim:—

A musical instrument mold comprising a

pair of mating outer mold members each formed with an elongated hollowed out portion and a lateral recess communicating therewith, said mold members being adapted to be filled with plastic material, inner mold members each formed as an elongated body having formed thereon a plurality of 30 projections adapted to be pressed through the plastic material in the outer mold members whereby to provide holes through the plastic material, said outer mold members being adapted to be superposed subsequent to the removal of said inner mold members 40 whereby to unite the edges of the plastic material, the edges of the mold members being formed with mating conical projections and recesses and being formed at their ends with transverse mating projections and recesses, and one mold member being formed 45 with a hole at the base of the lateral recess permitting the insertion of a strip into the molded material whereby to form an opening therein; the strip being subsequently removed.

In testimony whereof I affix my signature.

GUIDO BONDI.
